UNITED STATES PATENT OFFICE.

WILLIAM MAHLOCH, OF CHICAGO, ILLINOIS.

DESIGN FOR A WALL OR TABLE ORNAMENT.

43,699.

Specification for Design.

Patented Mar. 11, 1913.

Application filed July 26, 1912. Serial No. 711,735. Term of patent 7 years.

To all whom it may concern:

Be it known that I, WILLIAM MAHLOCH, a citizen of the United States, residing at Chicago, in the county of Cook and State of Illinois, have invented a new, original, and ornamental Design for Wall or Table Ornaments, of which the following is a specification, reference being had to the accompanying drawings, forming a part thereof.

I claim:

The ornamental design for a wall or table ornament, as shown.

WILLIAM MAHLOCH.
